ABSTRACT

A parallel voltage regulator having an improved factor of stabilization since a reference voltage from a Zener diode is used, this Zener diode being supplied, via a resistor, with a stabilized auxiliary voltage. The stabilized auxiliary voltage is obtained as the sum of an output voltage and of a voltage drop in a semiconducting diode polarized in a specific direction.

PARALLEL VOLTAGE REGULATOR

FIELD OF INVENTION

The present invention relates to parallel voltage regulators with improved factors of stabilization, and more particularly to regulators designed primarily for use in battery-type measuring instruments.

PRIOR ART

One voltage regulator of known type comprises a differential amplifier, a transistor of the n-p-n type, a Zener diode, and resistors.

These elements of the voltage regulator are connected in the following way:

A first terminal of a first resistor is connected with a first input terminal while a second terminal of a second resistor is connected with a first terminal of a third resistor, with the collector of the transistor which performs a regulating function, and with a first output terminal. The second terminal of the second resistor is connected with the cathode of the Zener diode and with a first input of the differential amplifier. A second terminal of the third resistor is connected with a first terminal of a fourth resistor and with a second input of the differential amplifier. The output of the differential amplifier is connected with the base of the regulating transistor. The second output terminal, the anode of the Zener diode, a second terminal of the fourth resistor, and the emitter of the regulating transistor are connected with a point whereat appears the reference potential of the system.

This system is designed for regulating output voltage irrespective of variations in load current and in supply voltage. Despite the fact that performance of the above described system is generally satisfactory, its use in battery-type measuring instruments is objectionable because of a high current input to the divider formed by the third and the fourth resistors connected together. Also, the output voltage obtained from this system is higher than the voltage of the Zener diode by the value of voltage drop in the second resistor, this voltage drop being usually no less than 1 V.

Therefore, if Zener diodes for current production and of a voltage of from 3 V upwards are used, the voltages obtained in the above-described system may be more than 4 V.

SUMMARY OF INVENTION

An object of the present invention is to eliminate the shortcomings and imperfections of the above-described known type of voltage-regulator system.

This object is attained by a new and simplified system in which the first terminal of the first resistor is connected with the first input terminal, while the second terminal of this resistor is connected with the first terminal of the second resistor and with the anode of the semi-conductor diode. The cathode of the semi-conducting diode is connected with the first input of the differential amplifier, with the collector of the regulating n-p-n type transistor, and with the first output terminal. The second terminal of the second resistor is connected with the cathode of the Zener diode and with the second input of the differential amplifier. The input of the differential amplifier is connected with the base of regulating transistor. The second output terminal, the anode of the Zener diode, and the emitter of the regulating transistor are connected with a point

whereat appears the reference potential of the system. The thusly constituted voltage regulator has a very good energy efficiency and it permits obtaining low output voltages of, for example, from 3 V up.

5 The above-mentioned qualities of the novel voltage regulator are, furthermore, achieved by including in the system a semi-conducting diode the voltage drop across which increases the stabilized output voltage supplying the Zener diode through the second resistor. 10 In this way, the current flowing through the Zener diode has a constant value governed by the voltage drop of the semi-conducting diode and by the voltage drop across the second resistor.

BRIEF DESCRIPTION OF DRAWING

An embodiment of the invention will next be described, by way of example, with reference to the accompanying drawing in which the sole FIGURE is a schematic diagram of a regulator provided in accordance with the invention.

DETAILED DESCRIPTION

A first terminal of a first resistor R_1 is connected with a first input terminal 1 of the regulator. The second terminal of the said resistor R_1 is connected via a junction J_1 with a first terminal of a second resistor R_2 and with the anode A_1 of a semi-conducting diode D_1 . The second terminal of the second resistor R_2 is connected via junction J_2 with cathode K_2 of a Zener diode D_2 and with the first input of a differential amplifier A. The cathode of the semi-conducting diode D_1 is connected via junction J_3 with the second input of differential amplifier A, and via junction J_4 with the collector C of an n-p-n type regulating transistor T and with a first output terminal 3. The output of the differential amplifier A is connected with the base B of the regulating transistor T. A second input terminal 2, the anode A_2 of Zener diode D_2 , an emitter E of the regulating transistor T, and a second output terminal 4 are connected with a point whereat appears the reference potential of the system.

The supply voltage U_1 is applied to input terminals 1 and 2. The reference voltage U for the differential amplifier A (said amplifier being the amplifier of error voltage) is supplied by the Zener diode D_2 . Voltage U is applied to the first input of the said amplifier A. The stabilized output voltage U_2 is taken from output terminals 3 and 4. A power absorbing resistor R_3 may be connected to the said output terminals.

50 In accordance with the operating principles of high-amplification-rate differential amplifier A, the output voltage U_2 is the same as the voltage in Zener diode D_2 . The voltage drop in resistor R_2 plus the voltage drop in Zener diode D_2 is equal to the output voltage U_2 plus the voltage drop in the semi-conducting diode D_1 provides that an already stabilized voltage is applied to the Zener diode D_2 through the resistor R_2 , thus improving the stabilization of the system.

An increase in auxiliary voltage by means of semi-conducting diode D_1 causes, first of all, that the drop of voltage in resistor R_2 is increased. The current of the Zener diode D_2 is proportional to the voltage drop in the semi-conducting diode D_1 , because this drop is equal to the voltage drop in resistor R_2 . In this way, the relative changes in the supply voltage U_1 are obtained, since the voltage drop in the semi-conducting diode D_1 depends only slightly on the current of diode D_1 . Thus,

the stabilization of the current of the Zener diode D_2 is obtained, this being the main objective.

What is claimed is:

1. A parallel voltage regulator having an improved factor of stabilization, said regulator being adapted for use in battery-type measuring instruments, said regulator comprising first and second output terminals, a differential amplifier including first and second inputs and an output, an n-p-n type regulating transistor, a Zener diode including a cathode and anode, a semi-conducting diode including a cathode and anode, and resistors each including first and second terminals, the first terminal of the first resistor being connected with said first input terminal, the second terminal of the said first resistor being connected with the first terminal of said second resistor, the second terminal of the said second resistor being connected with the cathode of said Zener diode and with the first input of said differential amplifier, a regulating transistor including a base, collector and emitter, the second input of the said differential amplifier being connected with the collector

of said regulating transistor and with said first output terminal, the output of the said differential amplifier being connected with the base of the said regulating transistor, and a point at which appears a reference potential of the system, the second input terminal, the anode of Zener diode, the emitter of the said regulating transistor, and said second output terminal being connected with the point of the reference potential of the system, the anode of the semi-conducting diode being connected with the junction between the first resistor and the second resistor, the cathode of the said semi-conducting diode being connected with the second input of said differential amplifier whereby the Zener diode is supplied, through the second resistor with an output voltage increased by the value of voltage drop across the semi-conducting diode, the sum of the current of a load and of the regulating diode flowing through the said semi-conducting diode.

2. A regulator as claimed in claim 1 comprising a load impedor coupled between said output terminals.
